SAFETY POSTER

George Nelson, New York, N.Y., assignor to Howard Miller Clock Company, Zeeland, Mich., a corporation of Michigan

Filed July 7, 1966, Ser. No. 2,968

Term of patent 14 years

(Cl. D96—12)

FIG. 1.

FIG. 2.

FIG. 3.

FIG. 4.

FIG. 5.

FIGURE 1 is a front elevational view of a safety poster embodying my design;

FIGURE 2 is a front elevational view of a modified form of the safety poster shown in FIGURE 1;

FIGURE 3 is a front elevational view of a second modified form of the safety poster shown in FIGURE 1;

FIGURE 4 is a front elevational view of a third modified form of the safety poster shown in FIGURE 1; and

FIGURE 5 is a front elevational view of a fourth modified form of the safety poster shown in FIGURE 1.

The dominant features of my design reside in the portions shown in full lines, said features being further characterized by a stylized figure of a workman wearing various types of bandages as shown. The safety poster is of no substantial thickness.

I claim:

The ornamental design for a safety poster, as shown and described,
